(74) Attorney, Agent, or Firm — Lerner, David,
Littenberg, Krumholz & Mentlik, LLP(57) **CLAIM**

The ornamental design for an anti-theft ink tag, as shown and described.

DESCRIPTION

FIG. 1 is a top perspective view of an anti-theft ink tag showing our new design;

FIG. 2 is a bottom perspective view thereof;

FIG. 3 is a rear elevational view thereof;

FIG. 4 is a front elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

In the drawings, the broken lines depict portions of the article that form no part of the claimed design.
